UNITED STATES PATENT OFFICE

HARRY H. HAZELTINE, OF EVERETT, WASHINGTON, ASSIGNOR TO THE ITECO COMPANY, OF PORTLAND, OREGON, A CORPORATION OF OREGON

DENTAL FLASK

Application filed May 26, 1930. Serial No. 455,826.

My invention relates to dental flasks and the like.

Dental flasks, as heretofore used in the making of artificial dentures, have commonly consisted of a metal vessel divided into two parts along a horizontal median plane and of such size and shape as to contain the molds of the said artificial denture in which a plate of rubber of the like is cast. The said plate bearing the artificial teeth in simulated arrangement and appearance to the natural teeth and gums.

In the making of artificial dentures in such flasks, no satisfactory means have been provided to prevent the molds from being improperly brought into apposition when the flask parts are assembled, with the result that the molds frequently are damaged and the artificial teeth disarranged from their proper arrangement.

Further, no means have been provided to facilitate the removal of the finished denture from the flask after the curing operation is completed, with the result that the finished denture is frequently injured.

Therefore, the object of my invention is to provide a dental flask having means adapted to facilitate the assembling of the flask parts without injury to the mold or denture to be cast therein.

A further object of my invention is to provide a dental flask adapted to facilitate the removal of the finished denture from the flask after it has been cured, without injury to the same.

Furthermore, in the making of artificial dentures, care must be taken when the flask is assembled that the abutting edges of the parts be brought into close contact at all points on their perimeters. Failure to bring the abutting edges of the flask parts entirely together causes the denture to be pressed more deeply into the mold at one place, then in another, thus throwing the artificial teeth out of alignment and causing misarticulation when placed in the individual's mouth.

Therefore, a further object of my invention is to provide a dental flask adapted to be pressed together with equal and compensated pressure over its entire perimeter margins,

whereby to assure that the entire abutting edges of the flask parts, when assembled, will be brought into close contact and "incomplete closures" and the like will be prevented.

To this end, I have provided a dental flask 55 consisting of three parts, a base having a central cavity therein adapted to receive one of the molds of the denture, an annular, split wall portion adapted to receive the other mold of the denture and to be mounted on said 60 base in alignment with the interior wall thereof, and a cover adapted to be arranged on said wall portion.

Further, in order to insure that the flask parts may be pressed together with an evenly distributed pressure exerted over their perimeter margins, I have provided the cover with three equally spaced upwardly projecting protuberances adjacent its perimeter margins, a resilient plate adapted to be arranged 70 on said protuberances and means carried by the perimeter margin of said base for drawing said plate down on said cover with the annular wall portion therebetween, whereby 75 their abutting edges will be brought into close contact.

These and other incidental features of my flask, the details of construction and the method of using the same are hereinafter fully described with reference to the accompanying drawings.

In the drawings:

Fig. 1 shows an elevation of my dental flask fully assembled;

Fig. 2 shows a similar view looking at the 85 bottom of the flask;

Fig. 3 shows a top view of my flask with the plate removed, the bolts being shown in section;

Fig. 4 shows a section taken on the line 90 4-4 of Fig. 3 and illustrates further details of construction;

Fig. 5 shows a section taken on the line 5-5 of Fig. 3;

Fig. 6 shows a perspective view of the annular wall portion; and

Fig. 7 shows a fragmentary section of the annular wall portion taken on the line 7-7 of Fig. 4.

Referring now to the figures: My dental 100

flask comprises three parts, a base *a*, an annular wall portion *b*, and a cover *c*.

The base *a* is internally recessed as at *d*, more or less in the general form of the mold of a denture, and is provided on its exterior with three equally spaced bosses *h* provided with bolt recesses *k* in which clamping bolts *i*, hereinafter further described, are adapted to be inserted.

External, vertical grooves *m* are provided at opposite points on the base *a*, arranged so that their adjacent sides are normal with and touch the transverse, median, vertical plane of the flask, as illustrated by the line *x* in Fig 2.

The annular wall portion *b* is similar in shape and contour to the base *a*, and is split at *r* and provided with lugs *t* adjacent the abutting ends, through which a bolt *s* is inserted, for holding them in abutment. By this construction, the contents of the flask may be conveniently removed by loosening the bolt *s* which will permit the annular wall portion to expand.

The said wall portion *b* is adapted to be seated on the base *a* in alignment therewith. Downwardly projecting lugs *5* are provided adapted to register with the recesses *m*. The lugs *5* and recesses *m* are formed with abutting plane faces, and the corners of the lugs are rounded or tapered as at *5a*, *5b*, the taper of the corner *5b* being slightly longer. The faces of the said lugs also are tapered adjacent their ends, as at *5c*.

By this construction, when one of the molds of the denture to be cured is placed in the base, and the other in the wall portion with the denture arranged between them, the two folds may be brought into juxtaposition by a gentle rocking motion from either side or transversely, so that neither the molds will be damaged or the denture disarranged.

Spaced ribs *6* are provided on the exterior of the wall portion *b* forming grooves in registration with the bolt holes of the bosses *h* on the base.

The cover *c* is similar in outline to the wall portion *b* and is provided with studs *10* on its under surface adapted to engage with the interior edge of the wall portion. Lateral enlargements *11* are formed on the rim of the cover in which bolt holes *12* are provided in alignment with the bolt recesses *k* of the bosses *h* on the base. Equally spaced, upwardly projecting protuberances *14* are provided on the upper surface of the cover arranged so as to lie in radial planes midway between the said bolt holes *12*. The said protuberances being so formed that their high points are adjacent the rim of the cover *c*.

The laminated, circular plate *15* of relatively stiff, spring-like metal is provided, adapted to be arranged on said protuberances,

having bolt holes *13* in registration with the bolt holes *12* of the cover *c*.

When my flask has been assembled with the molds and denture in place, in order that the flask parts may be pressed together with an evenly distributed pressure, so that the compression on the molds will be uniform throughout, the plate *15* is arranged on the protuberances *14* of the cover *c* and the before mentioned bolts *i* are inserted through the bolt recesses *k* so as to project upwardly between the ribs *g* on the wall portion with their ends projecting through the holes *12* in the cover and the holes *13* in the plate. Nuts *i'* are threaded on the ends of the said bolts, whereby the plate *15* is drawn down on the cover *c* to press the flask parts together.

By this construction, since the plate *15* is supported at three equally spaced points on the protuberances *14* and the strain of the bolts *i* are also at three equally spaced points, located, respectively, midway between the said protuberances, it will be immaterial whether all the nuts *i'* have been threaded down on the bolts *i* to the same degree, since any difference in strain between the bolts will be compensated by the said three point support and thus an equal and evenly distributed pressure will be exerted over the perimeter margins of said flask and the contents thereof.

A lug *17* having an eye *18* is provided on the under side of the base *a* for convenience in placing the flask and removing it from the retort by means of a suitable hooked instrument, not shown.

Further by locating the protuberance *14* on the marginal portion of the cover, the clamping force of the bolts is brought directly onto the abutting marginal edges and deformation of the cover due to the pressure is prevented, which might otherwise be transmitted to the material within the flask and create an unequal pressure upon the molds contained therein.

I claim:

1. A dental flask comprising separate sections, the upper face of the upper section provided at its perimeter with three equi-distantly spaced supporting projections all coming substantially to a point in a common horizontal plane, a resilient clamping plate supported upon said projections, compression means located at the perimeter of the flask between and equi-distant from said supporting projections, said compression means extending through said flask sections and said clamping plate, whereby the force of said compression means is uniformly applied in line with the walls of the flask, in drawing the sections of the flask together.

2. A dental flask comprising separate sections including a cover, the upper face of which is provided at its perimeter with three equi-distantly spaced supporting projections

all coming substantially to a point in a common horizontal plane, a resilient clamping plate supported upon said projections, compression means located at the perimeter of the flask between and equi-distant from said supporting projections, said compression means extending through said flask sections and said clamping plate, whereby the force of said compression means is uniformly applied in line with the walls of the flask, in drawing the sections of the flask together.

3. A dental flask comprising separate sections, the upper face of the upper section provided at its perimeter with three equi-distantly spaced supporting projections all coming substantially to a point in a common horizontal plane, a resilient clamping plate supported upon said projections, bolts located at the perimeter of the flask between and equi-distant from said supporting projections, said bolts extending through said flask sections and said clamping plate, whereby the force of said bolts is uniformly applied in line with the walls of the flask, in drawing the sections of the flask together.

4. A dental flask comprising separate sections including a cover, the upper face of which is provided at its perimeter with three equi-distantly spaced supporting projections all coming substantially to a point in a common horizontal plane, a resilient clamping plate supported upon said projections, bolts located at the perimeter of the flask between and equi-distant from said supporting projections, said bolts extending through said flask sections and said clamping plate, whereby the force of said bolts is uniformly applied in line with the walls of the flask, in drawing the sections of the flask together.
